UNITED STATES PATENT OFFICE.

JAMES C. CURTIS, OF CISCO, CALIFORNIA.

ROCKER ATTACHMENT.

1,210,429.

Specification of Letters Patent.

Patented Jan. 2, 1917.

Application filed December 3, 1915. Serial No. 64,898.

To all whom it may concern:

Be it known that I, JAMES C. CURTIS, a citizen of the United States, residing at Cisco, in the county of Placer and State of California, have invented certain new and useful Improvements in Rocker Attachments, of which the following is a specification.

My invention relates to chairs and more particularly to a rocker attachment for chairs.

The primary object of my invention resides in the provision of an improved rocker attachment for association with the legs of a stationary chair, said attachment being movable to convert a stationary chair into a rocking chair, novel retaining means being removably associated with the legs of the chair and the attachment for maintaining the attachment in a substantially rigid position.

Another object of my invention resides in the provision of a novel securing means associated with the rocker for pivotally connecting the rocker and the legs of a chair, said rocker being movable into engagement with the under surfaces of the legs of the chair and held in this position when the retaining means is placed into engagement with the securing means.

A further object of my invention resides in the provision of a rocker attachment, each rocker of which is formed in two sections, novel means being associated with one of the sections for holding the rockers in an inoperative position to permit of the use of the stationary chair in its usual manner.

A still further object of my invention resides in the provision of a device of the character described that is simple in construction efficient in operation and one that can be manufactured and placed upon the market at a minimum cost.

Other objects as well as the nature, characteristic features and scope of my invention will be more readily understood from the following description taken in connection with the accompanying drawings and pointed out in the claims forming a part of this specification.

In the drawings, Figure 1 is a side elevational view of my invention associated with the legs of a stationary chair to provide a rocking chair. Fig. 2 is an enlarged fragmentary side elevational view of my invention in a folded or inoperative position on

the legs of a stationary chair. Fig. 3 is an enlarged transverse sectional view taken on line 3-3 of Fig. 1 illustrating to advantage the construction of one of the securing elements.

Referring more particularly to the drawings in which similar reference numerals designate like and corresponding parts throughout the different views, I provide a stationary chair including a seat 1 having the back 2 connected thereto through the medium of braces 3, the sides of the back extending downwardly to provide rear legs 4 which are connected to the forward legs 5 through the medium of suitable cross bars 6. The construction of this chair forms no essential part of my invention, it being only necessary to show the same to illustrate the advantages of my invention which, incidentally, can be readily associated with practically any type of stationary chair now in use. Associated with the legs 4 and 5 of the chair is my improved rocker attachment.

The attachment in this instance consists essentially of two rockers including two sections 7 and 8 pivotally connected to each other through the medium of a hinge 9. In order to pivotally connect the sections 7 of rockers to the front and rear legs of chair, I have provided my improved connecting elements. In this instance, each of these elements is formed preferably from a single piece of flexible rod metal which is bent intermediate its ends to provide a coil 10, the arms 11 which extend therefrom being arranged in divergent relation with each other, while the outer ends of the arms are bent into parallel relation with each other and terminate in loops 12. The arms of the elements arranged on the inner sides of the legs are slightly longer than the arms of the elements on the outer sides of the legs. Two of these elements are arranged upon the inner and outer sides of each of the legs and pivotally connected thereto through the medium of a bolt 13 which extends through a transverse opening in the chair leg, the bolt being engaged by a nut 14. Loops 12 on the ends of the arms are connected upon opposite sides of the sections 7 of the rockers through the medium of suitable fastening devices 15. In order to hold the rockers 7 in substantially rigid engagement with the under surfaces of the legs after the rockers have been swung into this position, I have

provided a plurality of retaining rings 16, said rings being slidably mounted with the legs 4 and 5, and when the rocker section 7 is in the position described, the rings are 5 forced downwardly about the bolts into frictional engagement with the arms 11 of the elements and thereby maintain the parts in a substantially rigid position.

As is set forth, the rockers are formed of 10 two sections 7 and 8. Now, in order to hold these sections in substantially rigid position when the rocking chair is in operation, I have connected eyes 17, to each of the sections 8 adjacent the hinges 9 which are engaged at times by hooks 18 pivotally mounted on the sections 7. In order to hold the sections 8 against the rear chair legs when it is not desired to use the rocker attachment 15 and so prevent the sections 8 from interfering with a person walking close to the chair, I have connected other eyes 19 adjacent the free ends of the sections 8, which eyes are engaged by the pivotally mounted hooks 20 on the rear legs 4.

Although I have shown and described the preferred embodiment of my invention, I desire it to be understood that I am not to be limited to the exact details shown, however, I desire that great stress be laid upon 25 the arrangement of the improved rocker attachment movably associated with the legs of a stationary chair as well as the novel retaining means associated with the securing means for the rockers for removably 30 maintaining the rockers in substantially rigid relation with a chair.

From the above description taken in connection with the accompanying drawings, it can be easily seen that I have provided 40 a device that is simple in construction, containing but a few simple parts that can be cheaply manufactured and assembled and when assembled can be placed upon the market and sold at a minimum cost.

It will be understood that the above description and accompanying drawings comprehend only the general embodiment of my invention and that various minor changes in detail of construction, proportion and arrangement of the parts may be made within the scope of the appended claims and without sacrificing any of the advantages of my invention.

Having thus described my invention, 55 what I claim as new and desire to secure by Letters Patent, is:

1. A rocker attachment including, in combination with the legs of a stationary chair, a pair of rockers, means connected to 60 the legs of the chair and to the rockers whereby the rockers may be swung into either an operative or an inoperative posi-

tion with respect to the legs, and retaining means slidably mounted on the legs of the chair and held in an inoperative position 65 by the rockers and arranged to slide down the legs and about the pivotal connecting means to prevent movement thereof and consequently maintain the rockers in an operative position.

2. A rocker attachment including, in combination with the legs of a stationary chair, a pair of rockers, means for pivotally connecting the rockers to the legs of the chair to permit of the rockers being removably 75 arranged in engagement with the lower surfaces of the legs of the chair, and rings slidably mounted on the chair legs for engagement with the securing means for removably holding the rockers in an operative 80 position.

3. A rocker attachment including, in combination with the legs of a stationary chair, a pair of rockers, connecting elements each embodying a coil and spaced arms extending from the coil, means for pivotally connecting the coil and the elements upon opposite sides of each of the chair legs, means for pivotally connecting the outer end of the arms and the rockers, rings slidably 90 mounted on the chair legs and supported in an inoperative position by the rockers when the rockers are swung and arranged against the sides of the chair legs and also arranged to slide down the chair legs and about the 95 arms of the connecting elements subsequent to the swinging of the rockers into operative position beneath the chair legs to consequently prevent accidental disengagement of the rockers.

4. A rocker attachment including, in combination with the legs of a stationary chair, a pair of rockers, each of said rockers being formed of two pivotally connected sections, means for removably holding the rockers in 105 an extended position, means for pivotally connecting the rockers to the legs of the chair to permit of the rockers being swung into engagement with the lower surfaces of the chair legs, retaining means slidably 110 mounted on the chair legs and engageable with the pivotal connecting means to prevent movement of the connecting means to consequently removably maintain the rockers in position, and means for removably holding the rocker sections in engagement with the chair legs when in a folded or inoperative position.

In testimony whereof I affix my signature in presence of two witnesses.

JAMES C. CURTIS.

Witnesses:

I. B. YOUNG,
JULIUS GEORGE MOOX.
